STEAM GENERATOR

Walter Douglas La Mont, North Colebrook, Conn.,
assignor to W. D. La Mont Inc., Wilmington,
Del., a corporation of Delaware

Application November 13, 1933, Serial No. 697,788

22 Claims. (Cl. 122—250)

This invention relates to high speed steam and power producing apparatus and high speed methods of operating the same.

It deals with supercharged steam boilers and high speed, light weight, power plants using such a boiler, especially a boiler burning fluid fuels, in which all fluids; namely, the fuel, the air (for supporting combustion), and the main working fluid in the tubes of the boiler, each flow at extremely high velocities in the performance of their several duties.

It further concerns the coordination at all speeds, of the velocities of all flowing fluids, to insure the maximum and constant evaporation of the main working fluid in a minimum period of time.

It makes possible controlled and positive water input into each tube of the steam generator with controlled unidirectional flow or controlled non-unidirectional flow of the main working fluid in my steam generating elements as desired under conditions of high temperature radiant heat transfer at high rates of heat release.

A main object of my invention is to reduce the size, weight and cost of high speed steam generators and high speed steam power plants. I do this by increasing their speed of operation.

It is vital that the main working fluid especially, flow at least with some control of surging, or travel back and forth of steam and water in the steam generating tube at all times, under all steam making loads and speeds, substantially regardless of firebox temperatures or rates of heat release. It is also vital that a controlled quantity of water be positively put into each tube to assist with other means in controlling surging of working fluid in the steam generating tube.

I have found that by placing a pressure drop device at or near the inlet end of the tube and co-ordinating it with the quantity of water used in forced circulation, a positive input of water into each tube can be obtained in any desired quantity with a minimum of pressure drop, at any desired time, to meet any heat load condition imposed on the tube and by co-ordinating the quantity of water put into the tube with a pressure drop device at or near the outlet end of the tube, the hydraulic column of steam and water in the tube can be made as compact as desired to control surging or travel back and forth of the steam water in the tube or to entirely eliminate this surging as found necessary to insure proper operation at the steam generator.

In my co-pending application, Serial No. 686,

268, filed August 22, 1933, in which I disclosed how to obtain unidirectional flow, the inlet end of the tube is open, and a larger quantity of water would normally be used for operation of the steam generating tubes in this co-pending application than would be used if the water were metered into the tube in the desired quantity at or near the entrance of the tube. Also, while any degree of compactness of the steam and water column in the tube can be obtained to insure unidirectional flow in the above co-pending application, there is no means whereby the column of steam and water can be made more elastic and less compact than results from operation of the tube with a pressure drop at the outlet and an open inlet end with forced circulation.

Under certain low load conditions with lower heats than at full power, the column of steam and water can be made very elastic without bringing an undue surging or back and forth travel of steam and water in sufficient degree to interfere seriously with the proper operation of the steam generator. With any given maximum heat load for which the unit is designed, a certain degree of compactness of the steam and water column in the tube is necessary for proper operation of the steam generator. However, the designed heat loads of the steam generator may be of such degree that this necessary degree of compactness of the steam and water column in many cases may be less than that which would be obtained from operating the tubes with an open inlet end with forced circulation and a pressure drop at the outlet end.

Since the degree of compactness of the steam and water column in the tube is mainly controlled by the pressure drop device at the outlet co-ordinated with the quantity of water put into the tube for any given heat load, if the column of water and steam in the tube is more compact than is necessary or is not as elastic in character as it can be allowed to be, without interfering with the proper operation of the boiler; then more water is required than is necessary with the forced and positive water circulation input into each tube and/or more pressure drop in the pressure drop devices is used than is necessary.

By using a pressure drop device at or near the inlet into each tube in combination with a pressure drop device at or near the outlet of each tube, and coordinating each pressure drop device with the quantity of water used in the forced circulation, adjustments can be made as follows:

The pressure drop device at or near the inlet end of the tube can be adjusted to positively put

into each tube any desired quantity of water irrespective of the degree of compactness of the column of steam and water in the tube, the back pressures and pressure drops acting therein and/or the degree of heat load imposed on the tubes.

The pressure drop device at or near the outlet end can be adjusted to give any desired degree of compactness of the column of steam and water in the tube irrespective of the back pressure and pressure drops acting therein and/or the degree of heat load imposed on said tube.

By adjusting the degree of compactness of the steam and water column any degree of surging, or travel back and forth of water in the tube, can be controlled regardless of the back pressures and pressure drops acting therein and/or the degree of heat load imposed on each tube, and a minimum of water can be used with forced circulation with a minimum of pressure drop in the system.

In my co-pending application, Serial No. 692, 236, filed October 5, 1933, I disclosed how to obtain semi-unidirectional flow. In the present invention, by moving the pressure drop device from near the outlet end of the tube to another position toward the inlet end, any degree of semi-unidirectional flow can be obtained, and by using another pressure drop device at or near the inlet end of the tube, or at or near the point where steam is formed, all of the advantages of the invention in the above co-pending application can be obtained with semi-unidirectional flow together with added advantages of the present invention.

In this present invention, in referring to a pressure drop device it is not intended to confine the use of the pressure drop feature to a single device. An equivalent to the pressure drop features called for in this invention, can be obtained by other means, such as a combination of devices in various forms substituted for each single pressure drop device referred to.

Other objects of my present invention include; use of a minimum pressure drop in the steam generating tubes and positive and controlled and minimum necessary supply of water to each of the steam generating tubes or elements conveying working fluid through the water wall surrounding the combustion zone; and through the water passages or tubes of the water wall boiler; and steam generating elements exposed to convection heat to provide for the proper and adequate flow of water through the different parts of the steam generating apparatus and in such relation to the steam generated therein that an adequate flow of water may be maintained through each part and in suitable relation in one part relative to the other. It is a still further object of the invention to provide for the positive control of the amount of water delivered to or flowing through the different parts and to control the conditions under which it flows so as to accomplish the proper delivery to and flow through the different parts of the steam generating apparatus to suit conditions of steam generation in said parts.

A still further object is to increase the amount of water circulated and therefore the speed of the circulation of steam and water in the tube only when and as necessary with the increase in the rate of heat release, in order to increase the rate of heat transfer from the metal of the tubes to the water and steam by moving the forming bubbles of steam away from their point of formation faster, thus protecting the water wall tube

from the increasing heat to which it is exposed with every increase in the rate of heat release in the combustion chamber.

In accordance with my invention, the placing of pressure drop devices at or near the water inlet end of the tubes, or in that part of the tube exposed to radiant and/or convection heat, and the placing of pressure drop devices at or near the outlet ends of said tubes is a preferred position for these pressure drop devices, or orifices, if orifices are used as pressure drop devices.

Also in accordance with my invention, the pressure drop devices for use at or near the inlet end of each tube which are used in combination with pressure drop devices used at or near the outlet of each tube are placed preferably at any point in the tube beyond the point where steam begins to form, at the designed rate of heat release for the steam generator, thus insuring under the proper load conditions, the passing through the pressure drop devices of at least some steam with the water.

This immediately gives the advantage of a larger area for steam and water passage through the pressure drop device for a given pressure drop, and a given quantity of water, than would be possible if water alone were passed through the pressure drop device.

And also in accordance with my invention the pressure drop devices may be used in multiple and placed at different points along the steam generating elements, provided the object of preventing undue surging or travel of steam and water back and forth in a necessary portion of the length of the tubes is accomplished, and provided a minimum quantity of water can be used to accomplish the above purpose.

A steam generating apparatus operating in the manner set forth in this invention has certain advantages over my previous inventions because of the opportunity given to control the quantity of water put into each tube whether operating in the full condition, or less than sufficient to fill condition, and at the same time to control the degree of compactness or elasticity in the steam and water column in the steam generating portion, regardless of the rate of heat release, together with the opportunity to operate the tubes as full tubes and/or less than sufficient to fill, as desired, at different heat loads of the steam generator.

With a single orifice in the tube at the inlet end, practically the whole length of the tube is subject to a surging action as the rate of heat release increases especially if the tube is operated with the less than enough water to fill the tube condition. The tube has a non-compact, elastic column of steam and water throughout its length and sudden high heat effects on a local section of the tube will cause sudden local increase in pressure acting both ways, causing a compression of the column toward the inlet end as well as toward the outlet end resulting in a back and forth flow of steam and water in the tube past the orifice which may become violent enough to interfere with the proper operation of the boiler.

By adding an orifice toward the outlet end of the tube, the steam and water column in the length of the tube between the orifices can be made as compact as desired or given any desired degree of elasticity, thereby controlling the degree of interference to proper operation from back and forth flow within the tube. The tube under this condition has a controlled flow for that part of its length between the orifices, while

- the part of the length from the orifice to the outlet end may have some degree of surging or non-unidirectional flow, if the orifice is placed in some degree away from the outlet end toward the inlet end. This results in the tube as a whole giving what is termed semi-unidirectional flow, and these results can be accomplished with the minimum use of pressure drops and minimum quantity of water circulated.
- 10 As the rate of heat release increases, the need of advancing the orifice nearest the outlet end and along the tube, toward the end of the tube, likewise increases, until the exit end of the tube is finally reached.
- 15 The selection of the point along the length of the tube where the orifices can best be used is a matter of the general duty for which the apparatus is designed and for which it is to be put in use. The main factors to be considered are:
- 20 1. The rate of heat release in the combustion zone.
2. The degree of fluid compactness required to prevent surging in the hydraulic column from behind the orifice to the inlet end of the steam generating tube.
- 25 3. The degree of fluid compactness required to prevent surging or to control surging in the hydraulic column between the orifices.
4. The degree of fluid compactness required to prevent undue surging in the hydraulic column from immediately beyond the orifice toward the outlet end to the outlet end of the steam generating tube, in which some surging can be permitted without interfering with the proper operation of
- 30 35 the steam generator.
5. The amount of water most desirable for circulation.
6. The degree of pressure drop required coordinated with the quantity of water circulated, to insure one path flow and/or unidirectional flow and/or semi-unidirectional flow of the working fluid.
- 35 40 7. The size of orifice, or pressure drop device desirable to avoid clogging.
- 45 8. Mechanical and cleaning considerations.
9. The question as to whether it is better to operate a portion of the steam generating section with the so-called full tube condition, or with less than sufficient to fill the tubes condition.
- 50 I have found that with steam generator units, designed for certain load conditions, using an economizer that gives considerable steam generation at full load, or with an economizer which steams; the art of placing the orifices or pressure drop devices at the proper positions along the length of the economizer tube, to insure proper operation of the economizer tubes may be used in the same way as previously outlined for waterwall and convection generating tubes. The
- 55 60 placing of the orifice or pressure drop device past the point where steam may form is especially advantageous in the economizer to permit the use of larger orifices or pressure drop devices than would be possible if feed water only passed through such devices with sufficient pressure drop to insure one path flow under full load conditions, and by adding an orifice at or near the outlet end, the portion of the tube which may steam is made to operate properly.
- 65 70 In one of its aspects my invention is a high speed steam generator, whose water walls in the radiant heat releasing and receiving area, namely the combustion zone, and whose steam generating tubes and economizer tubes exposed to convection heat transfer in the convection heat
- zone, will not give an undue amount of surging of steam and water travelling back and forth in the tubes, but will have positive unidirectional, semi-directional, and/or controlled non-directional (i. e., controlled surging) flow of water in each tube, at all times, as found desirable or necessary, regardless of combustion conditions in the firebox the temperature of the gases entering the convection heat zone and the size or movement of large steam bubbles shifting from side to side in individual tubes, or groups of tubes, up to the maximum rate of combustion which the steam generator is designed to operate.
- 75 In its further aspect, my invention seeks to take this steam made at high speeds, then by means of a high speed steam engine, (preferably a steam turbine operating under high temperatures and pressures), convert this steam into power in a rapidly operating steam power plant where all auxiliaries are functioning at maximum speeds, and are closely co-ordinated and controlled to produce power in large quantities with the minimum in size, weight and cost of power producing equipment.
- Boilers in general use may be divided roughly into three main classes: (1) mass boilers; (2) James boilers; and (3) flash boilers.
- A mass boiler is a boiler which boils water in a mass, maintaining at all times a visually indicated water level in the boiler. It may either be a closed receptacle, a fire tube, or a water tube boiler, with or without forced circulation of water.
- James boiler (see British Patent No. 7,854, dated A. D. 1838, to William Henry James, inventor), are water tube boilers, having forced delivery of water to their steam making elements, and a complete and rapidly moving continuous circuit of water through the tubes of the boiler, with a water level apart from the boiler, but in circuit therewith, and with constant forced water circulation to the tubes. Such boilers might also be fire tube boilers.
- Flash boilers are practically instantaneous boilers, having water-steam-superheated-steam tubes, using no closed water circuit, and without any return circulation of water, but operating on a forced feed delivery of water to its steam-generating-superheating tubes.
- This present invention is particularly concerned with the improvement of high speed steam boilers, and power plants embodying the same, and methods of operating said boilers and said power plants. Where my invention, and/or any of its features, applies to flash boilers or mass boiling boilers and to high speed power plants using said flash boilers or mass boiling boilers, such improvements are well within the scope of my invention as herein described.
- While my invention has been described herein as relating to steam generating apparatus is intended especially for the generation of steam from water, it will be understood that the terms "steam" and "water" as used in the specifications and claims, are intended to include as equivalents, any liquids which might be handled by the novel process and/or apparatus herein described, resulting in the generation of any vapors which might be handled by, or be useful in connection with my process and/or apparatus, and it will also be understood that many of the novel features of this invention are applicable in other fields than that for which the apparatus herein

specifically illustrated and described is particularly intended.

An important object of this invention is to co-ordinate the quantity of liquid used in forced circulation in order to obtain positive input of water into each tube in sufficient quantity to protect each tube regardless of how rapid rates of heat release are obtained in the combustion chamber, up to the maximum heat effects for which said (combustion chamber) is designed to withstand.

Other objects and features will be particularly pointed out and disclosed hereinafter in the illustrations, descriptions, specification and claims of this present patent application.

In the drawings:

Fig. 1 shows a diagrammatic layout of my supercharged high speed steam generating power unit with a cross-sectional view of the high speed steam boiler forming a part thereof.

Fig. 2 is a detailed sectional view, with certain parts broken away, of a high speed steam boiler.

Fig. 3 is a sectional view of one form of working fluid distributor device used as a part of my high speed steam boiler.

Fig. 4 is a sectional view taken along line 4-4 in Fig. 3.

Fig. 5 shows a preferred form of pressure drop device for tube outlets, and

Fig. 6 illustrates another form of pressure device.

In my present invention, I preferably locate a pressure drop device 35B at the outlet end of each working fluid tube of my steam generator and a second pressure drop device 35A, is located at the inlet end of each working fluid tube of my steam generator for all designed heat loads and for high efficiency.

In my fluid heater apparatus as shown in my present invention, the apparatus is built and operated as follows: when preferably used with a means for forced circulation on the boiler.

Heating surface in the form of several tubes 53, is placed in the flow of the convection gases. The feed water connection is arranged to deliver water directly from the feed pump into each of these tubes of the fluid heater, via the feed stop and check valves.

The ends of the tubes 53, of the fluid heater are arranged in a compact group parallel to each other and secured in a disc 62B, which in turn, fits directly into the feed line discharge 18. Feed flowing in this line 18, will be driven by the pump directly into each fluid heater tube, but said flow striking the flat disc where it enters the fluid heater tubes would be disrupted. To prevent this, stream lining at the entrance of the tubes is resorted to, by placing a hollow cone shaped chamber 63A, in the feed line with its apex in the center of the feed line pointing away from flow of the feed approaching it, and its base equal to the diameter of the disc in which the fluid heater tubes are secured and said base resting on, and is secured to said disc 62B also the diameter of the base of the cone equals the inside diameter of the feed line. The cone has holes in it from its apex to its base, said holes being of inside diameter equal to the inside diameter of each fluid heater tube 53, and leading directly thereto.

With this arrangement the feed flow strikes the apex point of the hollow cone 63A, and is evenly distributed in a smooth fluid flow down each tube 53, of the fluid heater.

The feed pump 17, is connected directly to the

auxiliary turbine 6, which also drives the air supply and oil supply. The speed of this auxiliary turbine is controlled by the automatic combustion control 70, to give the proper air supply for combustion for any given load, but the size 5 and speed of the feed pump 17, when directly connected to this auxiliary turbine 6, is designed to make available at least, ample feed water for protection and proper operation of the fluid heater tube 53, at each load or rate of speed 10 required for delivering proper air for the given combustion condition of said load. The amount of water actually delivered however, by the feed pump 17, into the fluid heater tube 53, is controlled by a by-pass arrangement on the feed 15 pump 17, said by-pass 19A, being controlled by a valve 19, operated by the water level regulation device 24. A cross connection 73, controlled by automatic valve 75, and 76, is made from the discharge of the steam generator circulating 20 pump 28, to the inlet of the fluid heater.

The cross connection 73, connects to the inlet of the fluid heater tubes 53, beyond the feed stop and check valve 20, discharge on the fluid heater inlet side or before said discharge. The 25 cross connection has two automatic valves, 75 and 76, on a by-pass around the other automatic valve.

The fluid heater tubes 53, discharge directly into the water level cylinder 8, above the water 30 level of the steam generator apparatus.

When the water and/or steam discharge from the fluid heater tubes they pass the pressure drop device 35B, and a separator device 66, at the outlet end of each of said tubes. The pressure 35 drop device 35B, and the separator device 66, for each individual tube are very effective in obtaining a preliminary separation of the small volume of steam and water coming from each tube.

This new method of a mechanical means for 40 separation of steam and water from each individual tube, as it is discharged therefrom is important. By immediate separation action on the volume of steam and water coming from a single tube, the volume and resulting velocities to be 45 handled by the separating device, is much smaller than when attempting to separate the output of a group of tubes and the separation device can be designed to act more effectively if there is one for each tube instead of one for a group of tubes. 50 Further, in the case of the present invention, the pressure drop devices at the outlet of each tube 35B, are so designed that with the pressure drop effect, they give a preliminary breaking up of steam bubbles and separation of steam and water 55 as they discharge from the tube and this preliminary separating action is immediately augmented by the individual separating device 66, for each tube 53, just beyond the outlet pressure drop device.

Additional means for separation of steam and water discharged from all the fluid heater tubes 53, is further provided at their points of discharge said separation means 67, and 68, acting as a common device for each group of tubes as 65 distinct from the individual separating device in each tube. A still further separation of any steam mixed with water from the fluid heater occurs when steam from the fluid heater passes through the main separator 69, in the water 70 level cylinder 8, to go to the superheater 51. When the steam generating system is not to be used for extreme heat loads a pressure drop device 35A, is added to or near the inlet end of each tube 53, in addition to the pressure drop 75

device 35B, already placed at the outlet end of each tube.

In the superheater I use four small diameter, moderate length superheater tubes 51. At the steam inlet end these four tubes are secured to the water level cylinder 8, above the main steam separator 69. The four tubes then lead to the top of the combustion chamber metal casing covering or combustion chamber inlet end wall 221, 10 entering into the combustion chamber through the metal covering at four diametrically opposite points, where they are spiraled on a circumference which will bring them into the combustion chamber 106, tangent to the combustion chamber 15 side walls 220, as the spirals extend downwards on the diameter of said circumference.

If the four tubes entered the combustion chamber 106, together or nearly together, and they were then wound in the form a spiral they would 20 leave a considerable part of the combustion chamber wall exposed at the top, beginning at the spiral when the first turn is complete and at the bottom of the combustion chamber when the last turn is completed.

25 By entering the four tubes at diametrically opposite points on the circumference, or at widely separated points on the circumference the rise of each spiral as each tube passes above the tube starting a spiral just ahead of it, is 30 gradual and the section of combustion chamber wall left exposed is small, especially if the tube passing above the tube ahead of it is brought tangent or nearly tangent, to the tube ahead of it before the spacing of the spirals between 35 the two tubes is started. This brings the maximum width of the space of the combustion chamber wall not covered by a tube down to the width of the tubes diameter used.

When the four spiraled superheater tubes 40 reach the bottom of the combustion chamber they pass through the bottom casing or combustion chamber outlet end wall 222, at four diametrically opposite points in a manner similar to that described for the top, so that all parts of 45 the combustion chamber casing are properly protected.

The four tubes are then lead to a common point where they are secured in a compact manner to a disc 62A, with ends parallel to each 50 other and arranged to discharge directly into the steam lead to the turbine. At this point, each tube has a properly adjusted pressure drop device in its outlet end.

Saturated steam enters the tubes from the 55 water level cylinder 8, at the top and superheated steam leaves the tubes at the bottom of the boiler.

I have found that with supercharged combustion and high rates of heat transfer with high 60 velocities of steam flow, the column of steam in the superheater tubes, should be kept compact and the flow of steam in each superheater tube regulated to protect and insure proper operation of each superheater tube.

65 In the embodiment of the present invention, I preferably accomplish this purpose by using a pressure drop device at or near the inlet to each one of my superheater tubes and adjust its size with reference to the amount of steam flow desired for each tube, to distribute the flow of steam in each tube in the required quantity for various heat loads, also I add a pressure drop device to the outlet of each superheated tube and adjust its size with reference to the degree of 70 compactness desired for the steam column in each

tube for proper operation of that tube at various heat loads. However, it is within the scope of this invention to use pressure drop devices and locate same in my superheater tubes as disclosed in my co-pending applications: 686,268, of Aug. 22, 1933, covering my waterwall controlled unidirectional working fluid flow type of high speed generator; and 692,236, of October 5, 1933, covering my controlled semi-unidirectional working fluid type of high speed steam generator; or I 10 may for certain designs, omit the use of any pressure drop devices in my superheater tubes.

It is not intended to limit the scope of this invention to any particular form or use of pressure drop devices if any pressure drop devices are 15 used in my superheater tubes.

I accomplish this purpose by using pressure drop devices in each superheater tube, as disclosed mainly for steam generating tubes in my co-pending applications: 686,268, of Aug. 22, 20 1933, covering my waterwall controlled unidirectional working fluid flow type of high speed steam generator; and 692,236, of Oct. 5, 1933, covering my controlled semi-unidirectional working fluid 25 type of high speed steam generator; and in 25 this invention covering my controlled non-directional flow (or double orifice), type of high speed steam generator. In the embodiment of my present invention I place pressure drop devices at the outlet of each super-heater tube, adjusted to provide proper flow of steam in each tube to protect the tube and insure its proper 30 operation.

The waterwall tubing is spiraled in a manner 35 similar to the superheater tubing except the spirals are arranged to cover the bottom and top ends of the combustion chamber as well as assisting in protecting the side walls and superheater tubing. The main diameter of the waterwall spiral tubes is arranged so that the waterwall spiral coil as a whole fits inside of the superheater coil and just clears the superheater spiral coil making it possible to separate and replace 40 or repair either coil.

The waterwall tubing is made up of four small 45 diameter tubes 34, of moderate length. The ends of the four tubes are arranged parallel to each other in a compact group secured into a disc 62, which in turn is secured directly into the discharge lead 32, from the steam generator 50 circulating pump at the bottom of the steam generator so that the circulating water discharges directly into each tube. A cone distributor 63, with its apex pointed toward the oncoming circulating water is placed in front of said disc 62, 55 with holes leading to each tube as previously described for my fluid heater.

If the generator is to be exposed to extreme heat loads a pressure drop device is not placed in the inlet end of each tube.

If the generator is not to be exposed to extreme heat loads a pressure drop device 35A, is added to the inlet end of each tube for certain designs.

The four tubes 34, lead from the discharge end 60 of the circulating pump to four diametrically opposite points, at the bottom of the combustion chamber where they enter the bottom casing 222, and spiral around in a manner similar to that described for the superheater tubing 51, the 70 waterwall spirals at first being adjacent to and protecting the bottom casing 222, then travelling up along the sides of the combustion chamber, not adjacent to the casing 220, but on an inside diameter which fits the spiral coil inside of the 75

superheater coil 51. This diameter is held by the waterwall tubes 34, until they reach and become adjacent to the top casing 221. They now spiral inwards following the curve at the top 5 casing 221 and being adjacent thereto until they reach the central portion at the burner 2 where each spiral tube turns up through the top casing 221, at diametrically opposite points, through stuffing boxes, and then lead to the water level 10 cylinder 8.

The spiral coils of the waterwall tubing 34, are so spaced relative to the spacing of the superheater coils 51, that the superheater coils receive radiant and/or semi-radiant and convection heat 15 as previously described for the superheater in this invention.

Each waterwall tube 34, at its outlet end has a pressure drop device 35B, adjusted in it of proper size, relative to the quantity of water circulated 20 in it, and relative to the heat load imposed on it.

In addition, just beyond the pressure drop device 35B, which in itself is a separator of steam and water, and helps to break up steam bubbles; there is placed a mechanical separating device 25 66, to assist in the separation of the steam and water output from said tube only.

The circulating pump 26, takes water from the water level cylinder 8, drives it into each individual waterwall tube 34, and the steam with excess water, if there is any excess water, not evaporated from the tube is discharged back into the water level cylinder 8. Separation of steam and water occurring at the pressure drop device 35B, at the individual mechanical separator 66, 30 for each tube, at the separator for the group of waterwall tubes 68, and in the main separator 35 leading to the superheater 60.

The saturated steam enters the superheater 51, as described, and the excess water from the various points of separation of steam and water, if 40 there is any excess water over that evaporated in the waterwall tubes 34; falls to the water level in the water level cylinder 8, and is again picked up with water from the fluid heater for forced circulation 45 into the waterwall tubes 34.

In my present invention when I add the use of a convection steam generating gas passage 127, with its convection steam generating tubing 52, to the use of waterwall steam generating tubing 50 34, and superheating tubing 51, in combustion chamber 106, and fluid heater tubing 53, in tapered gas passage 115; I arrange for spiral cross flow of the gases in the convection steam generator tapered gas passage 127.

The convection steam generator gas passage 55 127, containing the convection steam generator tubing 52, is tapered with the passage decreasing in cross section as the gases pass through it from inlet to outlet, said taper being arranged to give 60 the proper velocity of the gas throughout its travel through the passage as the gas is cooled decreasing in volume and changing its density.

In my convection steam generator tapered passage 127, in some designs, I use three tubes although any number of tubes may be used to meet the proper requirements for a given design.

At the bottom of the steam generating apparatus these three tubes are arranged in a compact 70 group parallel to each other and secured to a disc 62C. This disc with a cone distributor 63B, is secured to the discharge lead from the boiler circulating pump 26, so that the circulating pump discharges directly into each convection generator tube 52, as described for the fluid heater tubes 53.

In operation water from the boiler circulating pump enters the convection generating tubes at the bottom of the steam generating apparatus as described past a pressure drop device in each tube 35A, and after travelling up the spiral tubes 5 the water and/or steam is discharged into the water level cylinder where the steam, if any, is separated from the water by the pressure drop device 35B, and mechanical separator 66, in the outlet of each convection generator tube 52, by 10 the separator 68A, for the outlet of all convection steam generating tubes 52, and by the main separator before any steam can reach the superheater tubes. The water from the convection generator tubes, if any, goes to the water level 15 chamber and is later picked up by the steam generator circulating pump to be used in recirculation and for evaporation.

In operation, feed water and/or circulation water enters the fluid heater tubes at the bottom 20 of the steam generating apparatus under the controls as previously described and after travelling up the fluid heater tubes in counter flow to the gases, the fluid water and/or steam is discharged into the water level cylinder where the steam, if any, is separated from the water by the pressure drop device and mechanical separator in the outlet of each fluid heater tube, by the separator for the outlet of all fluid heater tubes 25 and by the main separator before any steam can reach the superheater tubes. The water from the fluid heater goes to the waterlevel vessel and is later picked up by the steam generator circulating pump to be used in circulation and for 30 evaporation.

I have found that, with multiple tubes and high pressure it is advisable to use as few joints as possible. However, it is desirable to be able to at least, disassemble the main parts of the steam generating apparatus and separate the air pre-heater spiral tubing from the fluid heater, the fluid heater from the superheater and the superheater from the waterwall. 35

To facilitate such disassembly I make joints in the metal casings of the steam generating apparatus at the necessary places and single joints at each group of tubes at the bottom of the steam generating apparatus such as one joint for the fluid heater tubes, one joint for the superheater 40 tubes and one joint for the waterwall tubes. 45

The joints for the waterwall tubes and the superheater tubes are at that point on the diameter of the bottom casing so that both superheater tubes and waterwall tubes can be withdrawn from the combustion chamber without interference from said joints in their passage up through the combustion chamber. At the top the leads of all tubing go directly to the water level cylinder, all superheater tubes being at the highest level each with a joint, the waterwall tubes at a level just below without joints and the fluid heater tubes at the lowest level without joints. The water level cylinder has a joint at 65 each one of these levels said joints being all secured together by a single means so that disassembly of waterwall spirals, superheater spirals and generator spirals can be made without putting joints in all of the individual tubes at the 70 top.

The water level cylinder has the usual equipment of safety valve, main stop drain, water level indicator, and connection to circulating pump. It also has a water level regulator and the com- 75

bustion of the steam generating apparatus is controlled by an automatic combustion control.

Method of operation

5 A preferred embodiment of this invention is shown in Figure 1, which consists of a power unit with my supercharged high speed steam generator 1.

10 The steam generator 1, has its proper casings, passages, burner, and other parts necessary for the use of my waterwall tubes 34, in combustion chamber 106, my superheater tubes 51, in combustion chamber 106, my fluid heater tubes 53, in convection gas passage 115, and my spiral 10 cross flow air preheater with burnt gas tubes 65, and air passage 115, also my convection generating tubes 52 in tapered gas passages 127.

15 All piping, valves, auxiliaries and controls are shown for proper operation of my heat transfer surfaces together with the steam generator water level cylinder 8, for maintaining a water level in the system, a suction head for the circulation pump and a source of reserve power.

20 The main steam turbine 10, receives steam from the steam generator 1, exhausting to main condenser 11. The auxiliary turbine 6, drives on its shaft the air supercharger 5, condensate pump 16, feed pump 17, circulating pump 26, and oil pump 27.

25 A master combustion controller 70, operates all main controls to maintain a constant boiler pressure and to supply the boiler 1, with the necessary quantities of air, oil, feed water and circulating water for the proper operation of its heat transfer surfaces and to meet the various load demands.

30 The speed of the auxiliary turbine 6, is controlled by the master controller 70, to deliver the proper quantity of air.

35 The oil pump 27, and boiler circulating pump 26, have by-passes with control valves, operated by the master controller 70, to deliver the proper quantity of oil and circulating water as the auxiliary turbine speed is changed to meet the requirements for combustion.

40 The condensate pump 16, and feed pump 17, have a by-pass 19A, with control valve 19, operated by a water level regulator 24, on the water level cylinder 8, to maintain a water level in the system.

45 The boiler circulating pump 26, has a cross connection 73, to the feed inlet with control valve 76, operated by the master controller 70, to augment the supply of water for the fluid heater as the heat load increases.

50 The opening and closing of cross connection control valve 76, is modified by the opening and closing of the feed water level regulator by-pass valve 19, so that when one valve is closing the other valve is closing. This eliminates the use of unnecessary quantities of heated water for re-circulation in the fluid heater as changes in load occur.

55 The control valve 76, on cross connection 73, has a by-pass 14, with thermostat operated control valve 75. Thermostat control valve 75, is operated by a thermostat device 77, on the outlet end of a fluid heater tube 53. Whenever said tube 53, or the steam therein goes above the saturated temperature of the steam in the boiler thermostat element 77, opens valve 75, in by-pass 74, to protect the fluid heater tubes 53.

60 The general operation of the power unit is as follows:

Starting with a water level in the water level cylinder 8, water is sent by the circulating pump 26, to the waterwall tubes 34, and convection generating tubes 52, of the boiler 1. Water and steam discharges from waterwall tubes 34, and convection generating tubes 52, into the water level cylinder 8, where the steam and water are separated, steam going to the superheater tubes 51, and excess water going to the water level cylinder 8, where it is picked up by the circulating pump 26, with make up feed and re-circulated in the system.

10 The steam in the superheater tubes 51, becomes highly superheated and passes to the main turbine 10, to main condenser 11; also to auxiliary 15 turbine 6, and then to main condenser 11.

Condensate from main condenser 11, goes to feed water tank 15.

Starting with the feed water in feed water tank 15, this water is picked up by condensate 20 pump 16, and sent to feed pump 17. The feed pump 17, by means of the by-pass 19A, and control valve 19, supplies water to the fluid heater tubes 53, this supply being in accordance with the demands of the water level regulator 25 24, maintaining a water level in water level cylinder 8.

20 The circulating pump 26, by means of the by-pass 14, and thermostat valve 75, actuated by the thermostat 77, on fluid heater tube 53, and 30 by means of the cross connection 73, and control valve 76, actuated by the master combustion control 70, supply water for re-circulation in the fluid heater tubes 53, when necessary for protection and proper operation of the fluid heater 35 tubes, independent of the water level at different load demands.

25 The feed water and re-circulation water in the fluid heater tube 53, together with any steam formed, is discharged into the water level cylinder 40 8, where the water and steam, if any, is separated. The steam going to the superheater tube 51, and the water going to the water level in water level cylinder 8, to be used for maintaining a water level, for re-circulation and for 45 formation of more steam.

30 The more detailed method of operation of my power unit is as follows:

Starting

50

To start the boiler 1, after a shut down of the boiler and power unit, it is necessary after filling the system with water to a low water level in water level cylinder 8, to insure a supply of oil under pressure to the burner 2, to insure some 55 degree of atomization of the oil and mixing of the air for combustion.

35 With a slow fire, natural air draft can be used, until steam is formed to turn over the auxiliaries. In this case a hand oil pump is employed to force oil through line 61C, past opened valve 61D, to the burner, valve 61E being closed. Only a small quantity of oil is used and when ignited through burner door 212, there is sufficient air from the opening 105, through door 212, and from the air passages to carry on slow combustion until steam forms and the resulting pressure causes flow of steam under pressure from the superheater tubes 51, through the main steam line 9, through auxiliary steam line 7, past opened control valve 42, and into auxiliary turbine 6, driving auxiliary turbine 6, as it exhausts through exhaust lead 28, to exhaust lead 10A, of the main turbine to main condenser 11, to condensate line 14, to feed tank 15. Valve 75

61E, is then opened and valve 61D is closed, combustion then being carried on by the auxiliaries on the shaft of turbine 6.

When electrical power is available or when a 5 motor-generator storage battery system is used for starting, a motor on auxiliary turbine 6, drives the auxiliaries supplying all the air, oil and water for quick starting and operation of the power unit.

10 However, it is within the scope of this invention to use any known method of starting the steam generator.

15 From the time that auxiliary turbine 6, starts driving all the auxiliaries, the operation is as follows:

Feed water

20 Feed water, whenever it is necessary before and during the operation of the power unit, is put into feed tank 15, from the reserve feed tanks through filling line 46, past filling line valve 43, to maintain a supply of feed water in this tank for operation of the water in the system. Vent 47, in feed tank 15, is open to the 25 atmosphere.

25 Feed water is picked up by condensate pump 16 through condensate suction line 29, from feed tank 15, and delivered to the suction of the feed pump 17, through connection passage in the 30 casings of the two pumps, as long as the two pumps are being driven by auxiliary turbine 6, and there is water in feed tank 15.

35 Feed water is received from condensate pump 16, by feed pump 17, and discharged through feed pump discharge line 18, past feed stop and check valve 20, past feed water hollow cone distributor 63A, past fluid heater tube disc 62B, and into the fluid heater tubes 53; and/or the feed water from pump 17 in discharge line 18, 40 is by-passed through by-pass line 19A, past water level regulator control valve 19, back to condensate pump suction line 29.

45 Water level regulator valve 19, is operated by water level regulator element 24A, through pipe line 25.

50 The water level regulator element 24A, is attached with the gauge glass 23, to a point above and below the water level, in water level cylinder 8.

55 As the water level rises and falls in water level cylinder 8, the water level regulator element 24A, through pipe lead 25, opens or closes the water level regulator valve 19, in varying degrees depending on the height of the water in the water level cylinder 8. The water level regulator by-pass valve 19, closing or decreasing its opening with a fall in the water level and opening or increasing the degree of its opening with rise in the water level.

60 This opening and closing of the water level regulator valve 19, opens or closes in varying degrees the by-pass line 19A, from the feed pump discharge line 18, to the condensate pump suction line 29, thereby decreasing or increasing the 65 amount of make up feed water delivered into the fluid heater tubes 53, in accordance with the demands for maintaining a water level in the water level cylinder 8, independent of the speed of auxiliary turbine 6, driving condensate pump 16 and feed pump 17, and also independent of the 70 requirements of the fluid heater tubes 53, for their proper protection and operation against the heat loads imposed on them. In general, the feed input into the fluid heater tubes from the action 75 of the water level regulator valve 19, will be

normally increased with increase in heat load, requiring more make up feed and thereby causing a fall in water level, but often the water level may be rising or may be at too high a level or the water level may be raised by steam bubble 5 formation at a time of sudden increase in heat load and the water level regulator 19, may fall to close on the by-pass line 19A, or may remain open or may not move for some time from its partially opened position at the time of sudden 10 change in heat load thereby not increasing the input of feed water into the fluid heater tubes with increase of heat load. The action of the water level regulator valve 19, is always entirely dependent on the action of the water level. 15

Water forced into the fluid heater tubes 53, by the feed pump 17, and the action of the water level regulator valve 19, on by-pass line 19A, passes through the fluid heater tubes 53, in the convection burnt gas heat transfer zone passage 115, and discharges with steam, if any is formed, into water level cylinder 8, at the top, above the water level.

The feed input, as it discharges from feed pump discharge line 18, just before it enters the 25 fluid heater tubes 53, enters and passes through the apex of the hollow feed cone distributor 63A, which smoothly spreads and directs the flow into the holes in the hollow cone leading to each tube. This action gives a minimum disruption of the 30 flow of water to each tube and results in a more direct drive of the water into each tube. After the feed input passes the hollow cone distributor it enters a pressure drop device or Venturi shaped orifice 35A in each tube in the design used for 35 Fig. 1, which gives it a pressure drop delivery into the tube, which co-ordinated with the pressure drop device 35B at the outlet of each fluid heater tube 53, and the quantity of water put into each tube, gives full control of the degree of compactness 40 of the steam and water column in each tube for each heat load imposed on the tubes.

The water with steam, if any is formed, in the fluid heater tubes 53, passes through a Venturi shaped pressure drop device 35B, at the outlet 45 end before discharging into the water level cylinder 8. This pressure drop device 35B, is used to co-ordinate with the inlet pressure drop device 35A, of the design shown in Fig. 1, and the quantity of water circulated to give full control of the 50 compactness of the steam and water column in each tube and to insure unidirectional or controlled flow of steam and water in each tube.

At the outlet end of each Venturi shaped pressure drop device 35B, in each fluid heater tube, 55 there is placed a twisted strip of metal 66, (see Fig. 17) in this design shown in Fig. 5, which whirls the water and/or steam, issuing from the pressure drop device throwing the water outward, in the form of a cone shaped spray or film with 60 the main part of the steam in the central portion of the cone. Division walls or double baffles 67, are placed in front of each tube with a central opening in the inner wall pointing toward each tube which takes the steam through this opening 65 and causes the water to strike the baffle wall resulting in considerable separation of steam and water at this point. The preliminary centrifugal separation of steam and water from the output of each tube is obtained by means of the individual separator device 66 for that tube only.

After the discharging water and/or steam from each fluid heater tube has a preliminary breaking up of its steam bubbles and separation of the steam and water from the Venturi shaped pres- 75

sure drop device 35B, then a further augmentation of the separation action by adding centrifugal force from both the twisted metal strips 66, at the outlet of each tube, and the still further separation and collection of the steam and water with the baffles 67, having openings for steam in them, the water separated from the steam discharges to the water level for maintaining a water level, for re-circulation in the system and for replacing steam generated, and the steam passes through the main separator 69, to the superheater tube 51.

The steam generator circulating pump 26, picks up water from the water level cylinder 8, and sends it to the waterwall tube 34, the convection generator tubes 52, and/or to the fluid heater tubes 53.

The circulating pump 26, is driven by auxiliary turbine 6, which also drives the air supercharger 5, the condensate pump 16, the feed pump 17, and the oil pump 27, the speed of the auxiliary turbine 6, being controlled by the master combustion control 70, to deliver the required amount of air for combustion, although the speed of the auxiliary turbine might be used to control the amount of oil, feed water, and/or circulating water used, and it is intended to be within the scope of this invention to use any of these control means.

The circulating pump 26, picks up the water from the water level cylinder 8, through suction lead 31, discharging it through discharge lead 32, past waterwall hollow cone distributor 63, and past convection generator hollow cone distributor 63B, which acts on the circulating water in the same way as described for the feed hollow cone distributor 63A, past waterwall tube holding disc 62, and past convection generator holding disc 62C, and into each tube, past a Venturi shaped pressure drop device 35A, at the inlet into each waterwall tube 34, and convection generator tube 52.

The pressure drop device 35A, is used in each waterwall tube 34, and in each convection steam generating tube 52, in the same manner and for the same purpose as the pressure drop device 35A, described in this invention for the fluid heater tubes.

In Fig. 2 is also shown the location of pressure drop devices 350 at intermediate points of the tubes 34 which may be used in conjunction with the pressure drop devices at the inlets of the tubes or the outlets of the tubes for the purposes described above, relating to alternative locations of a plurality of pressure drop devices in the fluid conveying tube elements.

Water and/or steam discharges from the waterwall tubes 34, and convection steam generating tubes 52, at the outlet end, past a Venturi shaped pressure drop device 35B, past a twisted metal separator strip 66, and into the water level cylinder 8. Said pressure drop devices 35B and twisted metal separator strips 66, for each individual tube acting in the same manner on the water and steam coming from the waterwall tubes 34, and convection steam generating tube 52, as described in this invention for the fluid heater tubes 53.

As the water and steam from the waterwall tubes 34, and the convection generating tubes 52 enters the water level cylinder 8, the cone shaped water spray with steam in the center, strikes baffle walls 68, and 68A similar to the baffle walls 67, described, for the fluid heater tubes. The resulting separated steam goes through the main

separator 69, to the superheater 51, while the water falls to the water level where it is picked up again for re-circulation, by the circulating pump 26, with the make up feed water from the fluid heater tubes 51, where it is sent again as previously described, to the waterwall tubes 34, convection steam generating tubes 52, and/or the fluid heater tubes 53.

The discharge lead 32, of the circulating pump connecting it to the circulating pump suction 10 26, has by-pass line 45, with control valve 44, line 31.

The control valve 44, is operated by the moving rod 72, of the moving arm 71, of the master combustion control 70, which in turn is operated by 15 change in boiler pressure.

Since the master combustion control rod 72, moves with change in heat load demand, its movement can be used to operate the by-pass line 20 45, of the circulating pump 26, opening said valve 44, when load demands decrease, and closing said valve 44, when load demands increase, thereby varying the quantity of water available for circulation in the waterwall tubes 34, and/or the fluid heater tubes 53, to any amount desired for any 25 given heat load and setting of the valve.

The discharge lead 32, of the circulating pump 26, has a cross connected line 73, connecting to the discharge lead 18, of the feed pump 17, between the feed stop and check valve 20, of line 30 18, and the fluid heater tubes 53.

This cross connecting line 73, has a control valve 76, and a check valve 20, also a by-pass line 35 74, around valve 76, with a thermostatic operated valve 75.

When the valve or valves of the cross connecting line 73, are open, the circulating pump 26, delivers water positively into each fluid heater tube 53, for circulation and re-circulation in any 40 quantity desired, at any time, independent of the water level in water level cylinder 8.

Thermostatic valve 75, in by-pass line 74, is opened or closed by the action of a thermostat device 77, on fluid heater tubes 53. When the tubes of the fluid heater have insufficient water, 45 said thermostatic device becomes heated, as the steam formed within the tubes becomes superheated, causing the thermostat element 77, to open control valve 75, on by-pass line 74, on cross connecting line 73, opening cross connecting line 50 13, and thereby discharging circulating water from circulating pump 26, into the fluid heater tubes 53.

Thermostat element 77, is set to cause the opening of valve 75, at any time the temperature 55 in the fluid heater tubes goes above that of the temperature of saturated steam, at the designed working pressure of the boiler.

The action of the thermostat element 77, and valve 75, is independent of the water level and 60 also independent of the heat load except indirectly, when lack of water with the heat load might cause rise in temperature in the fluid heater above that at the temperature of the saturated steam.

Control valve 76, is operated by the master combustion control arm 71, moving rod 72, with change in heat load. This rod 72, is connected to the lever valve 76, from a lever point over on the water level regulator valve stem of water level 70 regulator valve 19. The connecting arm between rod 72, valve 76, and the lever point on valve stem 19, together with the location of both valves 19, and 76, are so arranged at the different heat load settings, that if the water level regulator 75

valve stem is in the open position, the rod 72, will have opened valve 76, but if the water level valve closes, it will close valve 76, or close it to any degree desired, as made with the valve and 5 arm setting.

When valve 76, is open, cross connection 73, is open, thereby discharging circulating water from circulating pump 26, into the fluid heater in any quantity desired.

- 10 The cross connection 73, with its valves and controls is mainly for the purpose of supplying water to the fluid heater in any desired quantity for co-ordination with the pressure drop devices in the tubes to protect said tubes and insure their 15 proper operation, at any time, only when and if, the supply of feed water coming into the fluid heater is insufficient to accomplish this purpose due to the water level condition and action of the water level regulation valve on the feed line.

20 *Steam*

The saturated steam from the waterwall tubes 34, convection generating tubes 52, and/or the fluid heater tubes 53, passing through the main separator 69, and into the superheater tubes inlet ends 51, at the top of the water level cylinder 8, as previously described; becomes highly superheated as it passes through the superheater tubing 51.

- 30 At the outlet of each superheater tube 51, I place a Venturi shaped pressure drop device 35B, adjusted to insure proper distribution of steam flow in each tube and compactness of the steam column in the coiled tubes 51.
- 35 The highly superheated steam discharges from the outlet ends of the superheated tubes 51, past the superheater tube holding disc 62A, into main steam line 9, where a second safety valve is generally located (not shown).

- 40 The superheated steam in main steam line 9, passes through main throttle stop valve 61, to main steam turbine 10, exhausting through exhaust lead 10A, to main condenser 11, where it is cooled and condensed back to water by cooling 45 water entering inlet 12, and leaving by exit 13, in main condenser 11.

The superheated steam from main steam line 9, also passes through auxiliary steam line 7, past auxiliary control valve 42, to auxiliary turbine 6, 50 which drives all of the main auxiliaries. The exhaust steam from auxiliary turbine 6, passes through auxiliary turbine exhaust line 28, to main exhaust line 10A, to main condenser 11, where it is condensed with the exhaust steam from main turbine 10. The condensate then passes through line 14, to feed tank 15, where it mixes 55 with any feed water from the reserve feed tanks, put into the feed tank 15, through filling line 46, past valve 43. The resulting water mixture then 60 passes through condensate suction line 29, of condensate pump 16, to pass through the system as previously described.

Fuel

- 65 The feed oil tank 38, is filled when necessary from the reserve fuel tanks through filling line 48, past stop valve 49. Vent 50, connects the fuel oil tank 38, with the atmosphere.

- 70 The fuel oil pump 27, picks up fuel oil from fuel oil tank 38, through fuel oil pump suction line 39, discharging it to the burner 2, through discharge line 40.

Fuel oil under pressure from the fuel oil pump 75 27, issues from the burner, in a finely divided or atomized spray, where it mixes with the air, and

after ignition keeps continually forming the gases of combustion in combustion chamber 106, at a rate of heat release proportional to the amount of air and oil mixture made available in the combustion chamber by input from the fuel oil pump 5 27, with its controls and the air supercharger 5, with its controls.

The fuel oil pump discharge line 40, has a lead 61G, going to the control valve 61H, on the master combustion control 70, for power operation of 10 its moving arm 71, and motion of its valve operating rod 72.

Oil passing through control valve 61H, on master combustion control 70, discharges through line 61F, to the suction line 39, of oil pump 27. 15

The fuel oil burner has a centrifugal atomizing chamber with by-pass opening at its rear through which oil from the fuel oil pump, not issuing from the burner opening into the combustion chamber is by-passed back to the suction 20 of the fuel oil pump suction line 39.

The fuel oil by-pass line 61A, has a lever control valve 61B, which controls the quantity of oil sent to the burner.

The master combustion control, 70, through its 25 moving arm 71, and moving rod 72, operates the fuel oil by-pass lever valve 61B, so that if the boiler pressure is lowered from load demand the rod 72, moves, closing the by-pass valve 61B, and increasing the oil output of the burner. If the 30 boiler pressure is raised from decrease in load demand, the master combustion control rod 72, is moved so that the by-pass valve 61B, is opened, decreasing the pressure in the centrifugal chamber of the burner and the input of oil into the 35 combustion chamber. In this manner a sufficient quantity of oil is automatically forced in the combustion chamber in proportion to the load demands maintaining a fairly constant boiler pressure throughout the system, at all load conditions. 40

Air

The air supercharger 5, driven by auxiliary turbine 6, picks up air from the atmosphere through its suction inlet 41, and by high speed 45 rotation with centrifugal action compresses and drives the air throughout the boiler air and gas passage system with the combustion gases against any pressure drop conditions occurring in the system.

The air leaves the air supercharger 5, through the supercharger air discharge line 119, which enters the circular air entrance dome passage 120, tangentially, giving the entering air a whirling motion in said passage.

Air from the circular air entrance dome passage still whirling, enters through and into the stream lined air passages 121, of the tapered spiral cross flow air preheater. The air, as it is forced at high velocity into said air preheater 60 air passage 121, past the spiral tapered air preheater burnt gas tubes 65, meets with more resistance to cross flow than to spiral flow along the tapered spiral coiled air preheater burnt gas tubes 65, which result in a combination of spiral flow 65 and cross flow of the air in its air passages 121, giving spiral cross flow of the air along the heat transfer surfaces. The spiral tubes 65, of the air preheater are wound around the circular tapered fluid heater outer casing 225, so that the air 70 continues to have the same whirling motion in the air preheater air passages as it had when leaving the circular entrance dome chamber.

Air leaving the tapered spiral cross flow air preheater air passages 121, still whirling in the 75

original direction, enters the circular air inlet passage 125, and then the circular air inlet burner chamber 122, to the burner guide vanes at the burner entrance 123.

- 5 The burner guide vanes augment the whirling of the air, leaving the circular air inlet chamber 122, without change of direction of the whirl, guiding the air into the burner throat passage 124, and on into the combustion chamber 106, 10 where it mixes with the atomized fuel oil from the burner to form the combustion gases.

Combustion gases

15 The combustion gases formed in the combustion chamber 106, from the mixed and ignited oil and air, are driven at high velocity throughout the burnt gas passages of the steam generator 1, by the oncoming air from the air supercharger 5.

20 The main part of the combustion gases in the combustion chamber 106, striking the bulbous central position of the combustion chamber outlet end wall 223, are dispersed toward the depressed and curved turn 224, of the combustion chamber outlet end wall 222, near the circumference and thereby guided smoothly into the combustion chamber circular burnt gas passage 114, 25 and then into the convection generating spiral tapered burnt gas passage 127. As the combustion gases pass down the sides of the spiral coiled waterwall tubes 34, and superheater tubes 51, in the combustion chamber 106, these tubes tend to whirl the air in the same direction it had when leaving the throat 124, and this air with the combustion gases, continues to whirl as it enters the 30 convection generating spiral tapered burnt gas passage 127.

35 Since the spiraled convection generating coils 53, in the spiral tapered convection generating passage 127, are coiled in the opposite direction to the waterwall coiled tubes 34, and superheater coiled tubes 51, in the combustion chamber 106, the combustion gases continue to whirl in the same direction they had when leaving the combustion chamber, as they travel through the convection generating passage 127, the circular outlet convection generating passage 126, and into the spiral tapered fluid heater passage 115.

40 Since the fluid heater tubes 53 are coiled in the opposite direction to the convection steam generating tubes 52, the gases continue to whirl in the same direction while passing through the fluid heater tapered spiral cross flow passage 115, as they whirled when passing through the convection steam generating gas passage 127.

45 The combustion gases travelling through the spiral tapered fluid heater passage 115, at high velocity, strike the coiled fluid heater tubes 53, meeting with more resistance to cross flow than spiral flow and resulting in a combination of spiral flow along the fluid heater tubes 53, and cross flow across them, giving spiral cross flow of the gases on the heat transfer surfaces.

50 The combustion gases leaving the spiral cross flow tapered fluid heater passage 115, are guided by the streamlined entrance into the spiral tapered air preheater burnt gas tubes 65, travelling in counterflow to the air on the other side of said tubes 65, in the air preheater air passages 121, to the stack gas passages 117.

55 The gases leaving the stack gas passage 117, enter the streamlined entrance 118, into stack and leave the Venturi shaped stack exit to the atmosphere.

I claim:

- 75 1. In a steam generator, a circuit for water and

steam generated therefrom comprising a vessel in which a water level is maintained, positive water circulating means connected in circuit with said vessel, a steam generating tube connected in circuit with said positive circulating means and to said vessel in a space therein unoccupied by water, said positive circulating means circulating water from said vessel through said steam generating tube, and fluid flow controlling means at the inlet and outlet of said steam generating tube 10 to control the flow of water and steam within said tube, said steam generating tube receiving water in quantity greater than is evaporated.

2. In a steam generator, a circuit for water and steam generated therefrom comprising a vessel in 15 which a water level is maintained, positive water circulating means connected in circuit with said vessel, steam generating tubes connected in circuit with said positive circulating means and to said vessel in a space therein unoccupied by water, said positive circulating means circulating water from said vessel through said steam generating tubes, and fluid flow controlling means near the inlets and outlets of said steam generating tubes to control the flow of water and steam 20 within said tubes, said steam generating tubes receiving water in quantity greater than is evaporated.

3. The combination set forth in claim 2 where- 30 in said fluid flow controlling means comprise pressure drop devices.

4. The combination set forth in claim 2 where- 35 in a steam and water separator is disposed in said vessel.

5. The combination set forth in claim 2 where- 35 in means for separating steam and water is disposed in said circuit operatively associated with said vessel and the steam generating tubes dis- charging thereinto.

6. The combination set forth in claim 2 where- 40 in means for separating steam and water are dis- posed in said steam generating tubes adjacent the outlets thereof.

7. In a steam generator, a circuit for water and steam generated therefrom comprising a 45 vessel in which a water level is maintained, positive water circulating means connected in circuit with said vessel, steam generating tubes connected in circuit with said positive circulating means and to said vessel in a space therein un- 50 occupied by water, said positive circulating means circulating water from said vessel through said steam generating tubes and fluid flow controlling means for controlling the flow of water and steam within said tubes comprising pressure drop de- 55 vices near the inlets of the tubes and at points intermediate the inlets and outlets thereof, said steam generating tubes receiving water in quantity greater than is evaporated.

8. In a steam generator, a circuit for water and steam generated therefrom comprising a vessel in which a water level is maintained, positive water circulating means connected in circuit with said vessel, steam generating tubes connected in circuit with said positive circulating means and to said vessel in a space therein un- 65 occupied by water, said positive circulating means circulating water from said vessel through said steam generating tubes and fluid flow control- 70 ling means for controlling the flow of water and steam within said tubes comprising pressure drop devices at the outlets of the tubes and at points intermediate the inlets and the outlets thereof, said steam generating tubes receiving water in quantity greater than is evaporated.

9. In a vapor generating circuit, the combination including a vapor liquid separation device, positive liquid circulating means operatively connected to said separation device, liquid conveying tubes operatively connected to said circulating means and to said separation device in a space therein unoccupied by liquid, said positive circulating means circulating liquid from said separation device into and through said liquid conveying tubes and pressure drop devices at the inlets and outlets of said tubes for controlling the flow of vapor and liquid mixtures passing therethrough, said liquid conveying tubes receiving liquid in quantity greater than is vaporized.
10. In a steam generator, a circuit for water and steam generated therefrom comprising a vessel in which a water level is maintained, positive water circulating means connected in circuit with said vessel, water wall tubes connected in circuit with said positive circulating means and to said vessel in a space therein unoccupied by water, additional steam generating tubes connected in circuit with said positive circulating means and to said vessel in a space therein unoccupied by water, said positive circulating means circulating water from said vessel through said water wall tubes and said steam generating tubes, and pressure drop devices near the inlets and outlets of said water wall tubes to control the flow of water and steam within said tubes, said water wall tubes and said steam generating tubes receiving water in quantity greater than is evaporated.
11. The combination set forth in claim 10 wherein a plurality of pressure drop devices are disposed in each of said additional steam generating tubes.
12. The combination set forth in claim 10 wherein said steam generating tubes are disposed in a convection passage of the steam generator and each of said tubes is provided with pressure drop devices near the inlets and outlets thereof.
13. In a steam generator, a circuit for water and steam generated therefrom comprising a vessel in which a water level is maintained, positive water circulating means connected in circuit with said vessel, water wall tubes connected in circuit with said positive circulating means and to said vessel in a space therein unoccupied by water, additional steam generating tubes connected in circuit with said positive circulating means and to said vessel in a space therein unoccupied by water, feed water preheater tubes connected in circuit with said positive circulating means and to said vessel in a space therein unoccupied by water, said positive circulating means adapted to circulate water from said vessel through said water wall tubes, steam generating tubes and feed water preheater tubes, and a plurality of pressure drop devices in each of said water wall, steam generating and feed water preheater tubes for controlling the flow of water and steam within said tubes, said water wall tubes, steam generating tubes and feed water preheater tubes receiving water in quantity greater than is evaporated.
14. The combination set forth in claim 2 wherein in a superheater tube is connected with the space in said vessel unoccupied by water, and a pressure drop device in said superheater tube.
15. The combination set forth in claim 2 wherein in a superheater tube is connected with the space in said vessel unoccupied by water, and a plurality of pressure drop devices in said superheater tube.
16. The combination set forth in claim 2 wherein in a superheater tube is connected with the space in said vessel unoccupied by water, and pressure drop devices in said superheater tubes at the inlet and outlet thereof.
17. The combination set forth in claim 2 wherein in the fluid flow controlling means near the outlets of said steam generating tubes comprise pressure drop devices operating to separate water from the steam.
18. The combination set forth in claim 2 wherein means for separating steam and water are disposed in said steam generating tubes adjacent the outlets thereof, and operating in conjunction with the pressure drop devices at the outlets of said tubes.
19. In a vapor generating circuit as set forth in claim 9 wherein said pressure drop devices are of proper size in relation to said liquid conveying tubes to obtain the desired flow conditions of the fluids therein.
20. In a steam generator as set forth in claim 13 wherein said pressure drop devices in each of said water wall, steam generating and feed water preheater tubes are of proper size in relation to the tubes in which they are disposed to obtain the desired flow conditions of the fluids therein.
21. The combination set forth in claim 2 wherein in a superheater tube is connected with the space in said vessel unoccupied by water, a plurality of pressure drop devices in said superheater tube and said fluid flow controlling means in said steam generating tubes being in the form of pressure drop devices, all of said pressure drop devices being of proper size in relation to the tubes in which they are disposed to obtain the desired flow conditions of the fluids therein.
22. In a steam generator, a plurality of tubes adapted to conduct a fluid, means for imposing a forced circulation of water through said tubes, a plurality of pressure drop devices in each tube adapted to control the passage of the fluids therethrough, a water level chamber connected with said tubes, and means near the junction of the discharge ends of said tubes with said chamber above the water level therein for separating the generated steam from the water collected in said chamber for recirculation through said tubes.

WALTER DOUGLAS LA MONT.
